UNITED STATES PATENT OFFICE

2,616,170

CUTTING PLATE OF DRY-SHAVING APPARATUS

Richard Keblusek, Eindhoven, Netherlands, assignor to Hartford National Bank and Trust Company, Hartford, Conn., as trustee

Application July 1, 1946, Serial No. 680,571
In the Netherlands November 4, 1942

Section 1, Public Law 690, August 8, 1946
Patent expires November 4, 1962

6 Claims. (Cl. 30—43)

1

There has already been proposed a cutting plate for a dry-shaving apparatus whereby the capacity of the apertures of letting through the hairs and the skin is adjustable so that it is possible to adapt the shaver to any growth of hair and to any degree of suppleness of the skin.

Another object of the invention is to render possible adaptation to the growth of hair and to the thickness of skin without any need of performing any manipulation on the cutting plate itself.

According to the invention, in the case of a cutting plate of a dry-shaving apparatus which exhibits apertures of different sizes, the large and the small apertures are grouped for this purpose in different running surfaces for the cutting member. This creates the possibility of utilizing different interchangeable cutting members which each cooperate with a group of apertures of a certain size which may be considered as ideal as possible for a determined growth of hair and for determined properties of the skin. Since the other groups of apertures are provided in one or more other running surfaces, they are not swept by the cutting member chosen and therefore take no part in the cutting operation.

It follows from the above that the number of groups of apertures also determines the number of possibilities of adaptation.

For a better understanding it may furthermore be mentioned here that a group may comprise only a single slit-shaped aperture.

For a further increase of the shaving capacity, it is possible to provide additional smaller apertures in the running surface of a group of apertures, by which means the shaving operation is accelerated.

In one embodiment of the invention the apertures consist of slits of decreasing, preferably of continuously decreasing width.

The apertures which take no part in the shaving operation should preferably be closed since it has been found that comparatively thick hairs which enter into these apertures are frequently clamped therein, causing the sensation of scratching. The apertures may be closed, for example, by covering them with the aid of an extremely thin removable cover plate provided so as to be slideable or rotatable.

It should be noted however, that when the comparatively large or small apertures are used in the shaving operation, the following distinction is observed. When the comparatively small apertures are used, the larger ones should be covered, but when the comparatively large aper-

2

tures are used, the smaller apertures may continue to take part in the shaving operation unless, compared with the hair thickness of the person who shaves himself, the dimensions of the smaller apertures are so small that even if they cooperate with a cutting member the hairs may be clamped in the slits which are too narrow for them.

Although it is possible each time to use different cutting members separately for each group of apertures, it is advisable, according to the invention, to utilize a single cutting member which has cutting edges located in separate running surfaces of different dimensions.

15 The invention will be explained more fully with reference to the accompanying drawing in which:

Figures 1—5 diagrammatically represent several embodiments of the invention.

20 Figure 6 is a sectional view taken along the line VI—VI of Figure 1.

Figure 7 shows a top plan view of a cutting member according to the invention.

Figure 8 is a cross-sectional view of the cutting member of Figure 7 taken along the line VIII—VIII.

Figure 9 diagrammatically shows a plan view of another embodiment of the invention.

Figures 10—12 are cross-sectional views in elevation of the cutting member for the embodiment shown in Figure 9.

Fig. 1 shows a cutting plate 1 of constant thickness having apertures 2 and 3 of different sizes which are grouped in different running surfaces 4 and 5 respectively for the cutting member. In the lateral elevation in Figure 6 the reciprocating cutting member is denoted by 6; its teeth 7 cooperate with running surfaces 4 provided with large apertures 2. The running surfaces 5 take no part in the shaving operation since between the teeth 7 the cutting member is provided with a continuous groove. Persons having a thin and supple skin which is unsuitable for the large apertures 2 may take use of the running surfaces 45 which are provided with small apertures by turning the cutting member 6 through 180°, as is indicated at 8, since the running surfaces and cutting edges which in both cases cooperate with one another are their reflected images.

Figures 2 to 5 show variations in the type of apertures in the cutting plate 1. Figure 2 shows large and small elliptical apertures 22 and 23 respectively. Figure 3 shows large and small circular apertures 32 and 33 respectively. Finally, Figures 4 and 5 show two types of con-

tinuously decreasing apertures, 9 and 29 respectively.

Since the apertures which are not operative may exert a scratching effect on the hairs which have not yet been cut off, it is advisable to cover these apertures with the aid of the cutting member itself. Such a cutting member is denoted in Figures 7 and 8 by 19. In the position shown, which corresponds to the position of the cutting member 6 in Fig. 6, the teeth 10 cooperate with the apertures 2 provided in the running surfaces 4 whereas the apertures 3 are covered by an uninterrupted second running surface which consists in itself of two tracks 12 and which are flush with the level of the running surface of the cutting edges 11 which are present. This cutting member may also be used, as illustrated in the lateral elevation of Fig. 6, in the position obtained by turning it through an angle of 180°.

In Fig. 9 the invention has been applied to a cutting plate for a rotary cutting member. The two different running surfaces 13 and 14 exhibit apertures 15 and 15' of different sizes so that at will either the running surface 13 with the large apertures or the running surface 14 with the smaller apertures may be utilized. The cutting member is constructed, for example, as shown in Figure 10. The cutting member 16 has legs 17 which sweep over the running surface 13 while after reversal of the cutting member, legs 18 cooperate with the running surface 14. Here again in order to cover the non-operative apertures the cutting member may be provided with uninterrupted additional running surfaces, formed in the present case by circular tracks as indicated in Figure 11 at 21.

It may furthermore be mentioned that, while paying regard to that which has been mentioned in this respect in the preamble of the specification, it is advisable to construct the cutting member for the plate shown in Fig. 9 in such a manner as shown in Fig. 12 so that the one set of cutting edges which cooperates with the smaller apertures is provided with an additional circular running surface 22 whereas the other set of cutting edges is widened as indicated at 23 to such an extent that it sweeps over the two running surfaces 13 and 14 with the result that the capacity is raised to its maximum.

These remarks also apply to the construction of the cutting member of Figs. 1 to 8 if it is constructed so as to be reversible in the same way as shown in Fig. 12.

Finally, in Figs. 3 and 9 still smaller apertures 20 and 30 are provided between the apertures of a determined group in order to raise the shaving capacity as far as possible.

What I claim is:

1. A cutter head for dry shaving apparatus, comprising a cutting plate having a first running surface and a second running surface, said first running surface being provided with a plurality of apertures having a given size and said second running surface being provided with a plurality of apertures of greater size than said given size, and a cutter member adjacent said cutting plate comprising a first cutting portion for selective engagement with said first running surface and a second cutting portion oppositely disposed from said first cutting portion for selective engagement with said second running surface, said cutting portions selectively engaging either said first or said second running surfaces by reversal of said cutting member.

2. A cutter head for dry shaving apparatus,

comprising a cutting plate having a first running surface and a second running surface, said first running surface being provided with a plurality of apertures having a given size and said second running surface being provided with a plurality of apertures of greater size than said given size, and a cutter member comprising a first cutting portion and an adjacently positioned first bearing surface and a second cutting portion disposed 180° opposite said first cutting portion and an adjacently positioned second bearing surface, said cutter member being adapted to operate in a plurality of positions relative to said cutting plate, and said cutting portions and said bearing surfaces selectively engaging either said first or said second running surfaces by reversing said cutting portions.

3. A cutter head for dry shaving apparatus, comprising a substantially flat cutting plate having a first running surface and a second running surface, said first running surface being provided with a plurality of slit-like apertures having a varying width and of a given size, said second running surface being provided with a plurality of apertures similar in shape to said first apertures but of greater size than said given size, a cutter member comprising a first cutting portion adapted to engage said first running surface and a second cutting portion disposed opposite said first cutting portion and adapted to engage said second running surface, said cutter member being adapted to operate in a plurality of positions relative to said cutting plate and said cutting portions selectively engaging either said first running surface in one position of said cutting member or said second running surface in the reversed position of said cutting member.

4. A cutter head for dry shaving apparatus, comprising a substantially flat cutting plate having a first running surface and a second running surface, said first running surface being provided with a plurality of circular apertures spaced apart and having a given size and said second running surface being provided with a plurality of circular apertures spaced apart and of greater size than said given size, said second running surface also being further provided with a plurality of minute apertures arranged between said apertures of greater size, and a cutter member comprising a first cutting portion and a second cutting portion disposed opposite said first cutting portion, said cutter member being adapted to operate in a plurality of positions relative to said cutting plate and said cutting portions selectively engaging either said first running surface in one position of said cutting member or second running surface in the reversed position of said cutting member.

5. A cutter head for dry shaving apparatus, comprising an annular cutting plate having a first annular running surface and a second annular running surface concentric to said first surface, said first running surface being provided with a plurality of apertures having a given size and said second running surface being provided with a plurality of apertures of greater size than said given size, and a cutter member comprising a first cutting portion arranged at a certain radial distance from its axis of rotation to engage said first running surface, and a second cutting portion disposed opposite said first cutting portion and arranged at a different radial distance to engage said second running surface, said cutter member being adapted to operate in a plurality of positions relative to said cutting plate and said

cutting portions selectively engaging either said first running surface in one position of said cutting member or said second running surface in the reversed position of said cutting member.

6. A cutter head for dry shaving apparatus, comprising an annular cutting plate having a first annular running surface and a second annular running surface concentric to said first surface, said first running surface being provided with a plurality of slit-like apertures having a given size and said second running surface being provided with a plurality of apertures similar in shape to said first apertures and of greater size than said given size, and a rotatable cutter member having a central planar support portion and comprising a first series of radially arranged cutter segments and an adjacently positioned annular bearing surface arranged on one side of said support portion and a second series of radially arranged cutter segments and an adjacently positioned annular bearing surface ar-

10

15

20

ranged on the opposite side of said support portion and arranged nearer to the axis of rotation than said first series of segments so as to engage said second running surfaces, said first and second series of cutter segments selectively engaging either said first running surface in one position of said cutting member or second running surface in the reversed position of said cutting member.
